CAM BURRING APPARATUS

John C. Baker, Worcester, Mass., assignor to
Norton Company, Worcester, Mass., a corpora-
tion of Massachusetts

Application April 19, 1938, Serial No. 202,920

8 Claims. (Cl. 51—58)

The invention relates to lapping machines, and contemplates an apparatus to take off the sharp edges of any surfaces of revolution such as a camshaft bearing or a cam.

One object of the invention is to provide an apparatus for smoothing the edges of the cams of an automotive camshaft. Another object of the invention is to provide an attachment for a cam lapping machine whereby the individual cams 5 can be burred. Another object of the invention is to produce a camshaft or similar article the sharp corners of which are eliminated. Another object of the invention is to provide an apparatus whereby a camshaft or similar article may be 10 simultaneously lapped and burred, thus achieving the burring of the camshaft without any substantial additional expense. Other objects will be in part obvious or in part pointed out hereinafter.

The invention accordingly consists in the features of construction, combinations of elements, arrangements of parts, and in the several steps and relation and order of each of said steps to one or more of the others thereof, all as will be 20 illustratively described herein, and the scope of the application of which will be indicated in the following claims.

In the accompanying drawings illustrating two of many possible embodiments of the mechanical features of this invention:

Figure 1 is a vertical sectional view of a portion of a camshaft lapping machine together with the cam burring apparatus of the invention;

Figure 2 is a fragmentary side elevation of one 35 of the cam burring heads;

Figure 3 is an enlarged sectional view taken on the line 3—3 of Figure 1;

Figure 4 is a plan view of the cam burring attachment on an enlarged scale;

Figure 5 is an elevation of the controlling lever and associated parts of the cam burring attachment, the view being taken looking toward the front of the machine;

Figure 6 is a fragmentary plan view of one end 45 of a camshaft lapping machine showing a modified form of cam burring attachment mounted thereon;

Figure 7 is a sectional view taken on the line 7—7 of Figure 6;

Figure 8 is a sectional view on an enlarged scale taken along the line 8—8 of Figure 7;

Figure 9 is a fragmentary sectional view taken along the line 9—9 of Figure 6;

Figure 10 is a fragmentary view on an enlarged 55 scale of one of the cam burring heads;

Figure 11 is a development of cam slots of a sleeve shown in Figure 8.

As conducive to a clearer understanding of the present invention, it is noted that patent to Herbert S. Indge and George E. Hulbert, No. 2,092,734 5 describes and claims a camshaft lapping machine for lapping the cams of an automobile camshaft, and also the bearings thereof. In such a machine the lapping is achieved with sandpaper. The cams and the bearings of the 10 camshaft have been previously ground and as a result of the grinding and lapping operations the edges of the various cams and also sometimes of the bearing portions are very sharp. In some automobile factories the sides of the cams 15 are not turned or ground but have the surfaces originally imparted to them by the forging process. The sharp edges of such camshafts, after the grinding and lapping operations, are also jagged. In these and also in the other cases the 20 workmen's hands are frequently cut by the sharp edges of the cams.

In shop terminology, when a sharp corner is smoothed off, it is said to be "burred." A sharp 25 jagged corner is also sometimes referred to as a "burr." The present invention provides burring apparatus by which is meant apparatus to remove or smooth the sharp edges of a work piece.

The prior patent to Indge and Hulbert referred to includes a table supporting the work piece 30 which is given a reciprocatory motion. Upon this table I may mount the cam burring apparatus in the form of an attachment. Thus I am enabled to perform the burring operation while the lapping operation is proceeding, thereby 35 avoiding any substantial additional expense for the burring of the camshafts.

Referring first to Figure 1, the machine of the aforesaid patent includes a table 20 mounted for reciprocation in the direction of the axis of 40 the camshaft 21 to be lapped. The machine also includes a bar 22 (and another one, not shown) supporting reciprocating slides 23. The slides 23 (only one of which is shown) have dovetailed portions 24 constituting ways supporting lapping arms 25, having complementary ways fitting the ways 24. By means of a gib 27 and screw 28 the several lapping arms 25 can be fastened in adjusted position opposite the cams 31 of a camshaft 21. This adjustment along the 50 length of the camshaft is provided so that the machine may handle different styles of camshafts.

Each lapping arm 25 has a long aperture 32 in which is located a slide 33. By means of a 55

spring 34 attached at its front end to a pin 35 extending between the sides of the arm 25 in the aperture 32, the slide 33 is urged in the direction of the cam 31. A master camshaft having 5 a plurality of master cams of the same size and angular position as the cams on the product camshaft 21 is provided to cause each slide 33 to reciprocate as the camshaft 21 revolves. This master camshaft is not shown herein and the 10 patent to Indge and Hulbert may be referred to. Anti-friction rollers 37 and 38 are provided, the rollers 37 being mounted in an adjustable bar 39 adjusted vertically by means of a screw 40.

Each slide 33 is provided with a nose member 15 42 which carries a yieldably mounted support 43 which serves as a support for the abrasive paper when in contact with the work. A roll of abrasive paper, not shown, delivers a strip 44 of abrasive paper or cloth to the yieldable member 43 of 20 the nose 42. This strip is wound up on a spool 45 carried by a stud 46 which is supported by a bracket 47 carried by the arm 25. One side 48 of the spool 45 constitutes a ratchet wheel and a pawl 50 is provided to prevent retrograde movement of the spool 45. The operator can wind up 25 a given amount of the strip 44 at any time when the operating section thereof has been worn out.

In order to prevent sidewise slipping of the 30 paper 44 on the nose 42, side guide plates 51 fastened to the sides of the nose 42 are provided. In order to prevent slipping of the abrasive paper 44 in a vertical direction, a strip of fairly coarse flexible abrasive cloth 52 extends around 35 the end of the nose piece 42 and is clamped in place theron by means of clamping members 53 and 54. The yieldably mounted nose piece 42 is held in a forward position by means of a spring 55, allowing a yielding engagement of the 40 abrasive paper with the periphery of the cam being lapped.

Referring now to Figure 4, the machine includes a work driving member 60 which is rotatably mounted on the table and which is rotated by a mechanism described in the aforesaid 45 patent. The machine also includes a tail center 61 supported by the table 20.

The foregoing is descriptive of the machine of the aforesaid Patent No. 2,092,734 and includes 50 apparatus cooperating with the present invention. Preferably all the instrumentalities described in the aforesaid patent will be used. The apparatus which is more particularly the subject of the present invention may conveniently be mounted upon the table 20 and will now be 55 described.

Referring now to Figures 1 and 4, I provide three frame members 65 near each end of the table 20 and in the middle thereof. Frame members 65 include ways 66 at the front thereof, a flat surface 67 at the rear thereof, and a gib 68 which may be tightened by means of a bolt 69. The ways 66 fit a portion 70 of the table 20 and the ways 67 and gib 68 fit a portion 71 of the 65 table 20. Thereby the frame members 65 may be adjustably fastened to the top of the table 20, the cross sections all along the table 20 being similar. Extending between and journaled in the frame members 65 is a shaft 75. Fastened 70 to this shaft 75 is a bell crank operating lever 76. This lever 76 has an arm 77a the outer end of which supports a shaft 78. Coaxial with the shaft 78 is a similar shaft 78a. At least one arm 77 is keyed to the shaft 75 and also supports the shaft 78. A pair of arms 77 support

the shaft 78a. Shafts 78 and 78a are always at the same level and move upwardly and downwardly in response to manual actuation of the bell crank lever 76.

The shafts 78 and 78a support a plurality of 5 bell crank brackets 79. Each bell crank bracket 79 has a square opening 80 receiving a slide 81 in which is located an eccentric 82 on a shaft 83. The shaft 83 is journaled in the frame member 65. Referring now to Figure 4, at the 10 right-hand end of the shaft 83 is fastened a spur gear 84 which meshes with a pinion gear 85 on the end of an armature shaft 86 of a motor 87. The motor may be mounted upon the tailstock 20 of the machine. Thus the shaft 83 is revolved and the several eccentrics 82 are rotated. As eccentrics 82 are located in the sliding blocks 81, the bell crank brackets 79 are oscillated about stationary pivots constituting the shafts 78 and 78a. The shafts 78 and 78a are shown in Figure 20 1 at the upper position thereof, in which position the brackets 79 hold abrasive stones 90 in contact with the several cams 31. By moving the bell crank hand lever 76 in a counterclockwise direction, the stones 90 are moved away 25 from the cams 31.

Considering now the manner in which the bell crank brackets 79 support the stones 90, and referring to Figures 1, 3 and 4, each bell crank bracket 79 has forked ends 91 supporting plates 30 92. The stones 90 may be made of any suitable abrasive suitably bonded, for example of crystalline alumina or silicon carbide abrasive grain bonded with vitrified bond or resinoid bond. On the other hand, they may be natural abrasive 35 stones. They are rectangular parallelopipeds in shape and at the ends they are cemented to holding plates 94. The holding plates 94 are pivoted at 95 to the supporting plates 92 and springs 96 connect the ends of the plates 94 40 opposite the pivots 95. Considering now Figure 3, it will be seen that the stones 90 are held at an angle to the sides of the cam 31 and, furthermore, they are resiliently pulled together. As the nose of the cam reaches the stones 90, they can 45 separate to allow it to move between them. The stones 90 abrade the edges of the cam and so are said to "burr" the cam.

Referring now to Figures 2 and 4, there are provided additionally arms 97 integral with certain brackets 79 which support narrow stones 98 spring pressed by a spring 99 against cam bearings 100. These cam bearings 100 are cylindrical portions and have oil grooves 101 the sides of which are burred by the stones 98.

The various parts mentioned will remain in the lower or inoperative position when moved thereto simply by the force of gravity assisted, if desired, by means of a spring 105 extending between frame member 65 and an arm 106 extending rearwardly from the bell crank lever 76. A screw 107 provides means for accurately locating the upper position of the parts and a detent 108 cooperates with a latch 109 pivoted between ears 110 extending rearwardly from the bell crank levers 76 to hold the lever 76 in the position shown. A hand grip lever 112 pivoted at 113 to the lever 76 is connected by a chain 114 to an arm 115 extending rearwardly from the latch 109, thereby to release the lever 76. A spring 70 116 causes the latch automatically to engage.

The operator places the camshaft to be lapped and burred between the tail center 61 and the work driving member 60 while the bell crank lever 76 is in forward or unlatched position. He 75

then moves the bell crank lever 76 rearwardly which raises the stones 90 and 98 against the cams and the grooves in the bearings. At any time the operator may do the other things to 5 prepare the machine for operation, as set forth in the aforesaid patent to Indge and Hulbert and then he may apply the power causing the shaft 21 to rotate, the table 20 to reciprocate, and the slides 23 and 33 to reciprocate, as set 10 forth in the aforesaid patent. At the same time, he energizes the motor 81 which causes the stones 90 and 98 to be oscillated. The rotation of the camshaft and the oscillation of the stones produces a very effective burring action to remove 15 the sharp corners from the several cams and also from the sides of the grooves in the bearing portions. The entire burring apparatus is carried by the table which in turn carries the camshaft and is, therefore, unaffected by the various reciprocating motions of the machine.

Figures 6 to 11 inclusive illustrate a modification of the invention which will now be described. As in the aforesaid patent, a sprocket 120 is mounted on the spindle 121 of the work 25 driving member 60. A sprocket chain, not shown, extends from this sprocket 120 to another sprocket eventually to drive the master camshaft, not shown. According to the present invention I mount an additional sprocket 122 to be driven 30 by the chain. This sprocket 122 is on the end of a shaft 123 journalled in a frame member 124 which, as shown in Figure 7, is fastened to the table 20. This frame member 124 has ways 125, a flat portion 126 at the rear thereof, and a 35 gib 127 which may be tightened by means of a bolt 128. The ways 125 fit on the portion 70 of the table and the ways 126 and gib 127 fit the portion 71 of the table, so that the frame member 124, and additional frame members substantially like it which are not shown, may be adjustably fastened to the top of the table 20.

The shaft 123 has fastened thereto a plurality of cams 130. Each cam 130 is housed in a box 131 which is supported by the shaft 123. Referring to Figures 7 and 8, extending radially outwardly from the box 131 is a sleeve 132 which may be integral with the box 131. This sleeve 132 has inclined slots 133 which are shown in the developed view of Figure 11. A tubular supporting member 134 has holes 135 on opposite sides thereof and a pin 136 extends through the holes 135 and the slots 133 into the head 137 of a tappet rod 138, the lower end of which bears against one of the cams 130. There are 55 as many of these mechanisms as there are cams on the product camshaft to be lapped.

The upper end of the sleeve 132 is blocked by a screw plug 139. In the sleeve 132 and between the plug 139 and the head 137 is a spring 140. This spring 140 holds the tappet rod 138 against the cam 130 and, therefore, the pin 136 rides up and down, following the shape of the cam 130. As it does so, however, it twists first in one direction and then in the other on account of the angularity of the slots 133. The tubular supporting member 134 must move up and down and also must oscillate with the pin 136.

The tubular supporting member 134 has an offset arm portion 141 which supports a stone holding device clearly shown in Figures 7 and 10. As therein shown, a stud 142 is attached to the top of the offset arm 141 and supports a pair of arms 143 and 144 one of which has a hub portion at the lower part of the stud 142 and the other of which has a hub portion at the

upper part of the stud 142. A spring 145 tends to separate the front portions of the arms 143 and 144, thereby urging together the upper and rearward ends of said arms. Springs 147 coiled around pins 148 and ears 149 and 150 serve to hold stones 151 to the arms 143 and 144. A central pin 152 projecting upwardly from the offset portion 141 prevents the stones 151 from approaching each other more than the desired amount when the stones 151 are not in contact 10 with a cam 31.

The axis of oscillation of the sleeve 134 extends almost tangent to the cylindrical portion of the cam 31. At all events, a somewhat irregular reciprocating and oscillating motion is imparted to the stones 151 which effectively burr the sides of the cams 31. The oscillating motion produces a rounding over of the edges of the cams 31 and the reciprocating motion, by causing periodically a greater relative motion 20 between the cam and the stone, increases the cutting action of the stones 146.

Extending forwardly from each box 131 is a short arm 155 through which extends a bolt 156 secured to a bar 157 supported by the frame 25 members 124. Around each bolt 156 is a spring 158. These springs hold the stones 146 against the several cams 31 and also permit the entire mechanism to swing in a counterclockwise direction when the noses of the cams 31 engage 30 the stones.

At any time the operator may remove all the stones 46 from cams 31 by turning a hand crank 160, Figure 6. As shown in Figures 6 and 7, the hand crank 160 is fastened to a long shaft 161 35 which extends the length of the table 20. Referring now to Figure 7, fastened to the shaft 161 at each end of the table 20 is a cam 162 (only one being shown) which engages a lever 163 pivoted on a stud 164 projecting from the 40 frame member 124. The other end of the lever 163 carries an angle iron 165 which extends the length of the table 20. Thus there is one long shaft 61 across the machine and one long angle bar 165 across the machine and a cam 162, lever 45 163 and stud 164 at each end of the machine. Turning of the hand crank 160 moves the angle iron 165 downwardly. All of the short arms 155 are in position to be engaged by the angle iron 165. Accordingly, by operating the hand crank 50 160, the operator may move all the burring devices away from the camshaft 21, and the shape of the cam 162 is such that they can readily be held in this lowered position.

Referring now to Figure 9, there is therein 55 illustrated an alternative device for burring the groove 101 in a cam bearing 100. Keyed to the shaft 123 is a cam 170. This cam 170 is located in a housing 171 which has integrally secured thereto a forked arm 172 supporting a burring arm 173 by means of a pin 174. A tappet rod 175 extends between the cam 170 and the burring arm 173 through the arm 172. A stone 176 which preferably has a tapered end is located 60 in the groove 101. This stone is cemented to a holder 177 which is held by split portion 178 of the burring arm 173. A spring 179 extends between a portion 180 of the arm 173 and the forked arm 172. This spring causes the retro- 70 grade motion to force the tappet 175 against the cam 170. A spring 181 extends between the bar 157 and the arm 172, thus holding the stone 176 against the cam groove 101 and also allowing the arm 172 to be depressed by means of the 75

angle iron 165 which engages the boss 182 on the arm 172.

It will thus be seen that there has been provided by this invention apparatus in which the various objects hereinabove set forth together with many thoroughly practical advantages are successfully achieved. As many possible embodiments may be made of the above invention and as many changes might be made in the embodiment above set forth, it is to be understood that all matter hereinbefore set forth or shown in the accompanying drawings is to be interpreted as illustrative and not in a limiting sense.

I claim:

- 15 1. Apparatus of the class described comprising means rotatably to hold a camshaft or the like, means to hold abrasive stones against corners of the cams thereof including means urging said abrasive stones towards each other, and means 20 angularly to oscillate said stones in contact with the cams.
- 25 2. In apparatus of the class described, means rotatably to hold a camshaft or the like, an abrasive stone, means to oscillate said abrasive stone about an axis substantially tangent to a work 25 piece element on said camshaft, and means to reciprocate said abrasive stone in a direction parallel to the axis of oscillation.
- 30 3. In apparatus of the class described, a table, a reciprocating polisher adjacent said table comprising an abrasive element and means to reciprocate it, and a cam burring attachment mounted on said table comprising a holder for abrasive stones, means to oscillate said holder, and means to raise and lower said holder.
- 35 4. In apparatus of the class described, a table, a sandpaper polishing head adjacent said table,

and a cam burring attachment on said table comprising a holder for abrasive stones, and means to reciprocate said holder.

5. A cam burring attachment comprising a pair of abrasive stones, a holder for said stones holding them so that a pair of surfaces thereof made a dihedral angle, spring means urging said stones towards each other to change the dihedral angle, means to oscillate the holder, and means to raise and lower the holder including 10 means to maintain the holder in raised or operative position.

6. In apparatus of the class described, a frame, means to clamp the frame to a table, a shaft supported by the frame, a hand lever to operate the shaft, arms extending from the shaft, a second shaft supported by the arms, bell crank levers supported by the second shaft, means to oscillate the bell crank levers, and abrasive stones carried by the bell crank levers.

7. In apparatus of the class described, a main shaft, cams mounted on said main shaft, boxes around said cams, tappets against said cams supported from said boxes, a sleeve around said tappets, connections between the tappets and the sleeves to cause the sleeves to be reciprocated by the tappets, inclined plane means to cause the sleeves also to be oscillated by the tappets, an offset arm on the sleeve, and abrasive stones carried by the offset arm.

8. In apparatus as claimed in claim 7, the combination with the parts and features therein specified, of means to raise and lower the boxes to hold the stones away from a camshaft or cause them to engage it.

JOHN C. BAKER.
